UNITED STATES PATENT OFFICE.

JOSEPH A. NIPCHILD, OF CLEVELAND, OHIO.

ENVELOPE SEALING AND PRINTING DEVICE.

Application filed February 10, 1923. Serial No. 618,208.

This invention is concerned with machines adapted to act on envelopes one after another to seal the same and if desired to print suitable matter thereon, the general object being the provision of a simple, efficient envelope sealing and printing device which is adapted to receive a stack of envelopes and eject them in a sealed condition.

A further object of the present invention 10 is to combine envelope feeding and flap moistening mechanisms with an envelope printing mechanism whereby the feeding and sealing of the envelopes may be effected and a further compressive sealing action on the 15 envelope flap may be obtained when printing the return address or other desired subject matter on the front of the envelope. A further object of the present invention is the provision of a novel envelope flap moistening 20 device which will apply moisture uniformly to the envelope flaps irrespective of the rate of speed at which the envelopes are fed to the device.

A still further object is the provision of 25 a novel envelope feed mechanism which may be incorporated in a device of the character referred to.

Other objects will become apparent from 30 the following description taken in connection with the accompanying drawings, and the essential features will be summarized in the claims.

In the drawings, Fig. 1 is a side elevation 35 of an envelope sealing and printing device embodying my invention; Fig. 2 is a plan view of the same; Fig. 3 is a side elevational section taken longitudinally of the machine substantially along the line 3—3 of Fig. 2; Fig. 4 is an enlarged transverse cross sectional elevation taken along the line 4—4 of Fig. 1; Fig. 5 is an enlarged cross sectional view taken through the envelope printing end of the device; Fig. 6 is a sectional elevation taken along the line 6—6 of Fig. 5; Fig. 7 is a fragmentary plan view of a flap moistening device and showing an envelope approaching a flap spreader; Fig. 8 is a similar view showing the relation of the flap spreader to the envelope when the gum on 50 the under side of the envelope is about to be moistened; Fig. 9 is an enlarged cross sectional view taken substantially along the line 9—9 of Fig. 7; Fig. 10 is an enlarged fragmentary view taken through the fountain of the gum moistener; Fig. 11 is a cross sectional view taken substantially along the

line 11—11 of Fig. 9 showing a preferred means for applying moisture to the gum on an envelope flap; Fig. 12 illustrates the position of the moistening device when the fountain thereof is to be removed for refilling; Fig. 13 illustrates a preferred manner of removably attaching the moistening device to the machine; Fig. 14 is a cross sectional view taken substantially along the line 14—14 of Fig. 12; Fig. 15 is a transverse sectional elevation taken along the line 15—15 of Fig. 5; Fig. 16 is a cross sectional plan view taken through the envelope feeding device along the line 16—16 of Fig. 4.

In accordance with the objects of my invention, I show in Fig. 1 a novel sealing device comprising a frame 20 preferably formed of a single casting member arranged to support the various mechanisms embodying my invention. An adjustable envelope receptacle is indicated at 22, an envelope feeding device disposed in juxtaposition to the receptacle is indicated at 23 and a flap moistener is shown at 24. Printing means 25 may be incorporated in the device at one end thereof as indicated at 25. The means for conveying the envelopes from the receptacle 22 to the moistener 24 and printing device 25, may comprise an endless friction belt 27 passing over end rolls 28 and 29 and arranged to act on the bottom face of the envelope, and a second endless belt 30 acting on the flap or top side of the envelope after the envelope has been fed past the moistening device. A preferred means for driving the friction belts 27 and 30 will now be described, and the various groups of mechanisms referred to, will be subsequently described in order.

As shown in Figs. 1 and 3, I have provided shaft members 32 and 33 which carry the bottom belt rollers 28 and 29, the latter members being disposed within the frame 20 and beneath a top table 20^a thereof. The table 20^a has suitable apertures formed therein whereby the rollers 28 and 29 may extend therethrough in tangential relation to the top surface thereof. The endless belt 27 thus passes around the roller 28 and along the top surface of the table 20^a. As shown in Fig. 3, the belt and table constitute a support for a stack of envelopes E when placed in the receptacle 22. The belt may be driven toward the feed device 23 by a manually operated crank 35 which turns a shaft member 36, the shaft 36 is disposed in

termidate the roller members 28 and 29 and constitute an axle for a large feed roller 38 preferably of the same diameter as the belt rollers 28 and 29 whereby the uppermost portion thereof may also be in tangential relation to the top surface of the table 20^a. Disposed on the opposite end of the shaft 36 is a gear member 40 which drives a similar gear member 42 mounted on the roller shaft 33, through an intermediate gear 41. The weight of an idler roller 26 serves as a belt tightening means.

The top friction belt 30 extends over small rollers 43 and 44, the former being mounted on a shaft member 45 which carries a gear 46 on one end and in engagement with the gear 42 on the bottom roller shaft 33. The shaft 48 which carries the roller 44 is driven by sprocket member 50 mounted on the outer end of the shaft member, a chain 51 and a sprocket 52, mounted on the roller shaft member 45 adjacent its small gear 46. The co-operation of the various rollers and belts in effecting the feeding, sealing and printing of the envelopes will be hereinafter described.

The envelope receptacle may comprise a side wall preferably formed by an upward extension 20^b of the side wall of the frame 20; a laterally adjustable side member 56 carried by a rod 57 supported by the extension wall 20^b and an upwardly and downwardly movable end baffle 58 which comprises part of the envelope feeding mechanism.

The envelope feed mechanism comprises the large bottom roller 38 mounted on the crank shaft 36, and a relatively small compression roller 59 resiliently mounted on the frame to be vertically movable, whereby an upward and downward movement of the roll during the passage of envelopes therebeneath will cause an alternate movement of the baffle member 58. This mechanism may comprise an upwardly extending slide member 60 having the lower end thereof in contact with the roll shaft 61 and the upper end acting on an adjustable means in engagement with a small lever member 62. The latter member is mounted on a rocker shaft 63 supported by bearing portions 64 depending from a bracket member 65 secured to the frame extension 20^b. The adjustable means on the slide member 62 may comprise a screw member 66 engaging a hump 62^a formed on the rocker lever 62. Small arms 68 depending from the rocker shaft 63 engage outwardly extending lug portions 58^a formed on the member 58.

The movable member 58 has the lower portion 58^b thereof extending toward the feed roll 59 whereby the envelopes in the stack E adjacent the bottom envelope are progressively urged thereagainst by action of the friction belt 27 on these envelopes.

As shown in Fig. 16, sliding engagement between the member 58 and the bracket member 65 may be provided by bent inner portions 65^a engaging the side edges and the back face of the member 58. The end of 70 the portion 58^b may be adjusted relative to the belt by manipulating the screw member 66. The member 58 should be adjusted to a sufficient height above the belt portion traveling along the top surface of the table 75 to permit passage of one envelope. When the bottom envelope is progressed to the opposed rolls 59 and 38 and is gripped thereby, the full weight of the member 58 is exerted upon the envelope as it is fed to the 80 moistening device and the bottom edge of the inwardly extending portion 58^b, thus prevents the feeding or passing of more than one envelope at a time; likewise the member 58 prevents the feeding of a second 85 envelope before the first envelope is moved out of contact with the feed roll 59. The spaced-apart relation of the roll 43 and the feed roll 59 is such that the roll 43 or belt 30 carried thereby will engage the forward 90 end of the envelope before the rearward end has passed from beneath the roll 59. This distance, accordingly, is less than the length of the smallest commercial envelopes in use. 95 It will also be noted that the spaced apart relation of the roll 59 and the member 58 determines the spacing of the envelopes when being conveyed by the belt.

The rolls 59 and 43 may be maintained in resilient relation to the rolls 38 and 29 respectively by flat spring members 70 disposed exteriorly of the frame 20 and fixed thereto by screws 70^b, see Fig. 13, and having means 70^a thereof extending upwardly and looping over the ends of the shaft members 61 and 45 as shown in Figs. 1 and 4, one of the loops being omitted on the spring disposed on the left hand side of the machine, there being a spring member 71 acting on a pin member 72 in place thereof.

The spreading of the envelope flap and the moistening of the gum thereon will now be described.

Disposed along the upper surface of the bottom friction belt 27 and between the rolls 59 and 43, is a flat fountain member 75 in the nature of a hollow arm which comprises the body of the envelope flap opening and moistening device. The member 75 is pivotally mounted, as indicated at 76 adjacent the right side of the machine, the mounting being such that the member 75 may be readily removed from the machine as illustrated in Fig. 13. This mounting comprises a bracket 77 having upwardly extending arms, formed as indicated at 78, to provide circular openings for receiving lugs 79 on the member 75. Upwardly extending slots are formed of such width as to permit the passage of lugs 79 when the 130

flat sides 79^a thereof are brought into alignment with the slots by swinging the moistening device outwardly to its detachable or filling position. The arcuate portions of the lugs engage the circular portions of the bracket openings when the member 75 is swung to operative position.

The interior of the member 75 comprises a water fountain arranged to feed moisture to bristle members 80, so positioned upon the outer portion thereof as to be exposed on the top and contact with the gum on the envelope flap when the envelope is moved from the roll 59 to the roll 43 by the belt.

The formation of the side edge of the member 75 is such that the envelope flap becomes raised as the body of the envelope is guided beneath the member 75. As shown in Figs. 7, 9 and 11, the edge of the member 75 disposed toward the feed roll, is tapered to approximate a knife edge as indicated at 81, there being a downwardly tapered surface 83 and upwardly tapered surface 82 meeting along the edge 81 whereby the forward end *e* of the envelope will pass beneath the member 75. The bristle supporting end of the member 75 is so formed that the knife edge 81 recedes backwardly toward the bristles 81. Thus, a substantial portion of the envelope will be disposed beneath the member 75 before the flap *F* thereof is engaged by any portion of the fountain member. As shown in Figs. 7 and 8, the body of the envelope is passing beneath the fountain member 75 while the flap is being guided upwardly by the knife edge 81.

To insure intimate contact between the gum portion of the flap *F*, and the wet bristles 80, I provide a spring member 85 which has one end 86 thereof bent upwardly to guide that portion of the flap first engaging therewith downwardly toward the bristles. The spring member 85 also acts to press the gummed surface of the flap into intimate contact with the moistened bristles 88. As shown in Fig. 10, a sufficient number of bristles are provided to obtain a relatively thick moistening pad, the lower portion of the pad being disposed within the fountain member 75 below the level of the water 87. The water thus is fed to the uppermost bristles by capillary attraction. The spring member 85 is swingably attached to the fountain member 75 by a screw member 85^a, whence the brush 80 may be readily removed.

Various means may be provided to maintain the water at the level referred to. I prefer however, an arrangement such as is illustrated in Fig. 10 which may comprise a reservoir or inverted container 88 with the open neck thereof in threaded engagement with an interiorly threaded portion 89, projecting from the upper surface of the

fountain member 75 adjacent the outer end thereof. This container is preferably formed of glass to permit visibility of the liquid contents. A gasket 90 may abut the end of the container and rest on a suitable shoulder formed interiorly of the fountain member, thereby preventing leakage of the water. Communication is afforded between the interior 91 of the portion 89 and the interior 92 of the hollow envelope spreading portion of the fountain member 75 by a restricted passageway 93. As shown in Fig. 14, the cross section of this passageway is considerably less than the cross section of either the interior cavity 92 or the interior space 91. A small vent 94 permits the ingress of air to the cavity 92.

The feeding action of this device is as follows:

The bottle 88 may first be filled with water and then attached to the member 75; the latter being swung outwardly from the conveyor belt and positioned as shown in Fig. 12, to prevent the spilling of any of the contents of the bottle when being attached. When the member 75 is swung inwardly to operative position upon the conveyor belt 27, the water feeds downwardly through the passageway 93 until a partial vacuum is created at the top, closed end of the bottle member 88, thus preventing a further feeding of the water.

The relation of the passageway 93 to the cavities 92 and 91 is such that this feeding action will cease when the water level approximates that illustrated in Fig. 10, the level being slightly above the top of the passageway 93. As the water in the cavity 92 is consumed, the level thereof comes below the top of the passageway 93 and permits an air bubble to escape from the cavity 92 upwardly to the air pocket in the top of the bottle member. A few drops of water will thus be permitted to flow from the bottle into the cavity 92. It will be seen that a constant water level is maintained relative to the gum moistening bristles 80 irrespective of the rate of speed at which the envelopes are fed through the machine.

I have arranged the printing mechanism in such relation to the feed and moistening devices that the printing mechanism becomes automatically active when an envelope is fed thereto by the conveyor belts 27 and 30. Any desired character of printing may be affected on the address or bottom side of the envelope, the usual subject matter of the printing being in the nature of a return address placed adjacent the upper left hand corner. The printing operation is such as to be also effective in further compressing the moistened gum on the flap, thus bringing about a more thorough sealing of that portion of the flap immediately

over the surface of the envelope which is being printed.

Such a printing device may be embodied in a variety of mechanisms. In the drawings, a preferred form of simple mechanism is shown, which may comprise a revolving drum 100 supported on a shaft member 102 mounted on a swingable bracket 101 attached to a supporting frame 104 secured to one end of the main frame 20 of the device. The disposition of the drum is immediately below the roller 44, and the shaft 102 therefore has its axis lying in a vertical plane passing through the axis of the roll 44, whereby the latter member may serve as a platen.

To insure the proper functioning of the belt 30 and roll 44 as a platen, I provide adjustable means for resiliently maintaining the roll 44 in contact with the envelope as it passes through the printing mechanism, which may comprise flat spring members 103 secured to the frame member 101 and acting on downwardly extending pin member 105 slidably positioned in the side walls 104^a of the frame. The compressed relation between the roll 44 and the printing drum 100 may be varied by the adjustment of the screw member 103^a acting on the flat spring member 103.

The revolving drum 100 is arranged to be intermittently operable and may be of such dimension that the circumference thereof will be of sufficient length to support an electroplate or other suitable printing form to print at least one-third of the surface of the envelope. The revolving movement of the drum 100 is initiated by the action of an envelope being fed by the rolls 43 and 44, and the belt 30 against upwardly extending projections comprising a flat member 107 secured to the roller 100 in such position as to be interposed in the path of the moving envelope. The forward edge of the envelope is thus pressed against the members 107 and starts the revolving movement of the roll and the printing surfaces of the form 108 then engage the envelope and the continued revolving is effected by the pressure of the positively driven platen roll 44 upon the back of the envelope. The rotation of the drum is thus continued until all of the printing surfaces of the form 108 have completed contact with the under surface of the envelope.

To continue the revolving motion of the drum after the printing has been effected and to reposition the members 107 adjacent the rolls 44, I provide a resilient means in the form of a spring member 110 having one end secured to a swingable support 101 and the other end attached to a small link 111, the small link being pivotally connected to a flange 102^a of the shaft 102 and the pivotal connection having an eccentric relation to the shaft 102. During the first half revolu-

tion of the drum, 100, the spring member 110 will be stretched and act in opposition to rotation of the revolving of the drum 100 in the manner described. However, as the pivotal center of the member 111 passes the vertical center of the drum shaft, the spring acts upon the drum to continue the revolving movement thereof, thus bringing the members 107 into juxtaposition with the platen roll 44. The revolving operation may be continued by the succeeding envelope being fed by the rollers and plate.

The application of ink to the printing surfaces of the form 108 may be effected in any suitable manner. A very convenient and compact inking device may comprise an inking roller having a hollow perforated core 114 and an outer felt covering 115, the interior of the roll being of sufficient dimension to contain a quantity of ink which may be gradually fed through the roll. The particular concealed location of this inking device as shown in Fig. 15 is preferred to a more exposed position to prevent contact of the ink roll with the envelopes.

To permit ready access to the inking device, the support 101 is pivotally mounted as shown in Figs. 5, 6 and 15, upon a pin member 116 rigid with the frame member 104 and is arranged to also support the inking roll. The printing drum support 101 may be maintained with the drum 100 in cooperative relation with the roll 44 by a lock pin 118 having the inner pointed end thereof engaging in an opening 119 formed in the wall of the bracket member 101. A spring member 120 serves to maintain the pin 118 in proper engagement with the bracket member. The upper portion 101^a of the bracket 101 is suitably slotted to permit engagement with the ends of the shaft 113 of the printing device. The ends of the shaft 113 are also engaged by depending portions 122 of an envelope supporting bracket 123 which is disposed beneath the lower stretch of the belt 30 and between the end of the main frame 20 and the platen roll 44. The depending portions 122 are provided with slots extending in a horizontal direction as shown in Fig. 3, whereby an outward swinging movement of the drum supporting bracket 101 will carry the printing roll out of engagement therewith. If it is desired to use the device for envelope sealing purposes only, the drum member 101 may be swung downwardly to an inoperative position.

From the foregoing description of my invention, it is to be seen that I have provided a very compact device for effecting the sealing and printing of envelopes after the letter content, which the envelope is to carry, has been placed therein. The action of the feeding mechanism is dependent solely upon the presence of an envelope between the feed

rolls. The thorough and proper moistening of the gum on the flap of the envelope is effected by a device which is extremely simple when considering the function which it 5 fulfills, and the positive and continued movement of the envelopes through the device is assured by the novel arrangement of the friction belts which feed the envelopes into a printing mechanism with sufficient force 10 to effect the intermittent operation of the printing device. The arrangement of the printing device is such that a further compressing of the moistened gum flap is obtained.

15 I claim:

1. In a device of the character described, the combination of an envelope receptacle, an endless friction belt associated therewith and arranged to feed an envelope from the 20 bottom of a stack of envelopes contained in the receptacle, said friction belt arranged whereby the top stretch of the belt may contact with the bottom envelope of the receptacle, a feed roll disposed above the belt 25 and in contact therewith and a baffle disposed between the envelope stack and said feed roll, and actuated by vertical movement of the said roll.

2. In a machine of the character described, 30 the combination of an envelope receptacle having an end wall thereof movable to block the passage of an envelope, an endless friction belt comprising the bottom of the receptacle and adapted to act upon the bottom 35 envelope of a stack positioned in the receptacle, a pair of feed rolls adjacent to said movable wall whereby an envelope being moved from the receptacle by the belt would immediately contact with said rolls, the axis 40 of said rolls being relatively movable, supporting shafts of the rolls and mechanism connecting the movable shaft with said movable wall in such manner that a downward movement of the wall is effected 45 when the edge of an envelope is engaged by the said feed rolls.

3. In an envelope sealing device, the combination of an envelope magazine, a frame having a flat top surface, an endless friction belt arranged to carry envelopes along the top surface of said frame, a feed roll positioned adjacent the envelope receptacle and above said belt and cooperating with said belt and being relatively movable therefrom, and means actuated in response to the movement of said feed roll and movable in 50 timed relation with said feed roll, for acting on the stack of envelopes positioned in the magazine to prevent the feeding thereof by 55 said belt.

4. The combination of an envelope magazine, a frame having a flat top surface, an endless friction belt associated with the envelope receptacle in such manner as to act upon the bottom envelope positioned therein 65 and to carry said envelope along the top surface of said frame, a pair of feed rolls adjacent the envelope receptacle and cooperating with said belt in advancing the envelope from the magazine subsequent to a preliminary movement of the envelope from the receptacle, said feed rolls being relatively movable, means acting on a stack of envelopes positioned in the receptacle to prevent the feeding thereof by movement of the belt 70 and actuated upon movement of one of the rolls when engaging the forward end of the envelope being carried by the belt.

5. A machine of the character described, 75 an envelope receptacle having an end wall thereof movable to block the passage of an envelope, an endless friction belt comprising the bottom of the receptacle, and adapted to act upon the bottom envelope of a stack positioned in the receptacle, a pair of feed rolls 80 adjacent to said movable wall whereby an envelope being moved from the receptacle by the belt immediately contacts with said rolls, the axes of said rolls being relatively movable, supporting shafts for the rolls and 85 mechanism connecting the movable shaft with said movable wall in such manner that when the edge of an envelope is engaged by the said feed rolls, an upward movement of the roll is effected which tends to force the 90 end wall downwardly.

6. A machine of the character described, 95 the combination of an envelope receptacle, a vertically disposed stack member, a feed roll movably disposed adjacent the receptacle 100 and adapted to be engaged and raised by a fed envelope, connecting mechanism between the feed roll and the stack member and operative upon the engagement of an envelope with the feed roll to cause a choking movement of envelope stack member to prevent 105 the passage of more than one envelope under the feed roll.

7. The combination of an envelope receptacle having a support and a movable wall 110 at an angle thereto, means for moving an envelope from the receptacle past the end of the movable wall, means moving in proportion to the thickness of the envelope for permitting a corresponding opposite movement 115 of said wall.

In testimony whereof, I hereunto affix my signature.

JOSEPH A. NIPCHILD.
